UNITED STATES PATENT OFFICE.

ALEXANDER K. SUTHERLAND, OF MILWAUKEE, WISCONSIN, ASSIGNOR TO MOE-BRIDGES COMPANY, OF MILWAUKEE, WISCONSIN, A CORPORATION OF WISCONSIN.

LIGHTING FIXTURE.

Application filed April 19, 1926. Serial No. 102,960.

This invention has for its object to provide a lighting fixture of the type used on the side walls of bathrooms, kitchens, halls and the like, wherein a shell-like opal glass shield or 5 semi-globular shade surrounds the horizontal incandescent lamp, and relates to a novel holder for such shield or shade permitting it to be quickly and easily attached or detached without requiring the usual threaded 10 means.

Another object of the invention is to provide such a holder which will firmly and securely support the shield or shade against accidental disengagement.

With the above and other objects in view the invention consists in the lighting fixture as herein claimed and all equivalents.

Referring to the accompanying drawings, in which like characters of reference indicate 20 similar parts in different views,

Fig. 1 is a sectional view of a lighting fixture constructed in accordance with this invention;

Fig. 2 is a similar view of a modification 25 thereof, and

Fig. 3 is a perspective view of the shade or shield holder.

In these drawings, 10 indicates a base or bracket which may be suitably mounted on a 30 side wall and terminates in a front vertical flange 11, within which is clamped a lamp socket 12 of the type known as a sign receptacle. The two members of this socket are connected together by a threaded engagement, which enables them to clamp the flange 11 between them. Also clamped in this manner is a ring 13, preferably of spring sheet metal, such as bronze, provided at its upper edge with a forwardly extending curved 40 spring lip 14 bent upwardly to form a curved hook conforming to the outline of the collar member of the sign receptacle 12 and bearing thereon. At its lower edge the ring 13 is provided with a forwardly extending curved 45 spring lip 15 also conforming to the outline of the collar member of the sign receptacle 12 and bearing thereon.

The incandescent lamp 16 supported in a 50 horizontal position by the lamp socket 12 as usual is surrounded by the semi-globular shade or shield 17, the reduced neck portion 18 of which is engaged on the hooked lip 14 and is held firmly in place thereon by its further engagement with the spring lip 15. In

order to mount the shade on its support, it is 55 inclined so as to first engage its neck portion 18 with the hook and then, by swinging it on said hook, the lower part of the neck portion is brought into bearing against the yielding spring lip 15, the spring action of which 60 serves to draw the shade into a firm seating relation with the flange at the end of the base 10, where it is held firmly against vibration or turning. To detach the shade it is only necessary to reverse this action by lifting it 65 out of engagement with the spring lip 15 and then removing it from the hook member. Thus the shade is attached and removed without the necessity for turning screw-threaded parts as heretofore and, by merely exerting 70 gentle pressure on the shade itself, reducing the danger of breaking the shade and avoiding the necessity for removable parts that may be injured when removed and unsuitable 75 for further use. The shade support of this invention permits of the shade being turned to throw the light as desired and securely holds it in any position as the ring remains fixed and the hook 14 supports the weight 80 while the lip 15 prevents disengagement from the hook.

If it is desired to permanently attach the ring 13 to the base 10, the edges of the flange around the central opening may be bent outwardly through the ring 13, in the manner shown in Fig. 2, and pressed thereagainst as at 19, or the hook and bearing lip may form a permanent part of the base in any other manner.

While the hook and tongue may be sufficiently heavy to be self-sustaining, it is possible to make them of light material inasmuch as they are re-enforced against collapse by their fitting against the collar member of the sign receptacle lamp socket 12.

Though the invention is particularly adapted to lighting fixtures of the wall bracket type, it is obvious that it may be used with ceiling lighting fixtures.

What I claim as new and desire to secure 100 by Letters Patent is:

1. A wall bracket lighting fixture comprising a base, a sign receptacle lamp socket fitting in an opening of the base and engaging the edge of the opening between the clamping members of the lamp socket, a metal ring also received between the clamping members of the lamp socket and having the edge of the 105

base passed through it and turned over thereon to permanently connect it with the base, said ring provided with a forwardly projecting upwardly bent hook and provided with a 5 forwardly projecting spring lip opposite the hook, and a shade having a reduced neck portion engaged on the hook and having the spring lip bearing thereon.

2. A wall bracket lighting fixture comprising 10 a base, a sign receptacle lamp socket fitting in an opening of the base and engaging the edge of the opening between the clamping

members thereof, a metal ring also received between the clamping members of the lamp socket and provided with a forwardly projecting upwardly bent hook and also provided with a forwardly projecting spring lip opposite the hook, both the hook and the spring lip bearing on the lamp socket for re-enforcement, and a shade having a reduced neck portion engaged on the hook and having the spring lip bearing thereon.

In testimony whereof, I affix my signature.
ALEXANDER K. SUTHERLAND.
